CLAIM

The ornamental design for an extruded side panel for a charging station, as shown and described.

DESCRIPTION

FIG. 1 is a front view of an extruded side panel for a charging station showing the claimed design;

FIG. 2 is a rear view of the extruded side panel for a charging station of FIG. 1;

FIG. 3 is a top view of the extruded side panel for a charging station of FIG. 1;

FIG. 4 is a bottom view of the extruded side panel for a charging station of FIG. 1;

FIG. 5 is a left view of the extruded side panel for a charging station of FIG. 1;

FIG. 6 is a right view of the extruded side panel for a charging station of FIG. 1;

FIG. 7 is a perspective front, top, right view of the extruded side panel for a charging station of FIG. 1;

FIG. 8 is a perspective front, top, left view of the extruded side panel for a charging station of FIG. 1;

FIG. 9 is a perspective rear, top, right view of the extruded side panel for a charging station of FIG. 1; and,

FIG. 10 is a perspective rear, top, left view of the extruded side panel for a charging station of FIG. 1.

The broken lines in the drawings illustrate portions of the article that form no part of the claimed design.
